SCREW DRIVER

David K. Tremaine and Darleen Tremaine, both of
3158 Marathon Drive, San Diego, Calif. 92123

Filed Mar. 17, 1972, Ser. No. 235,875

Term of patent 14 years

Int. Cl. D8—02

U.S. Cl. D8—82

Fig. 4

FIG. 1 is a perspective view of a screw driver, showing our new design;

FIG. 2 is a side elevational view from the other side thereof;

FIG. 3 is an end elevational view as taken from the left hand end of FIG. 2; and

FIG. 4 is a bottom plan view thereof.

We claim:

The ornamental design for a screw driver, as shown.
